UNITED STATES PATENT OFFICE

125,097

DESIGN FOR A WATCH FOB PLATE OR
SIMILAR ARTICLE

Herman Tabor, Chicago, Ill.

Application Nov. 16, 1939, Serial No. 88,321

Term of patent 7 years

To all whom it may concern:

Be it known that I, Herman Tabor, a citizen of the United States, residing at Chicago, in the county of Cook and State of Illinois, have invented a new, original, and ornamental Design for a Watch Fob Plate or Similar Article, of which the following is a specification, reference being had to the accompanying drawing, forming a part thereof.

Fig. 1 is an enlarged front elevation of a watch

fob plate or similar article, showing my new design.

Fig. 2 is a right end elevation of the same.

Fig. 3 is a fragmentary plan sectional view of the same, taken as indicated by the line 3—3 in Fig. 1.

I claim:

The ornamental design for a watch fob plate or similar article, substantially as shown.

HERMAN TABOR.
